UNITED STATES PATENT OFFICE.

FRANZ CARL TEUFL, OF OIL CITY, PENNSYLVANIA

FUEL-INJECTION VALVE FOR OIL ENGINES.

Application filed May 2, 1922. Serial No. 557,855.

To all whom it may concern:

Be it known that I, FRANZ C. TEUFL, a citizen of the United States, residing at Oil City, in the county of Venango and State of Pennsylvania, have invented certain new and useful Improvements in Fuel-Injection Valves for Oil Engines, of which the following is a specification.

The objects, construction and operation of 10 my improved fuel-oil injection valve for oil engines, are herein set forth with sufficient clearness, to enable others skilled in the arts to which its construction and use respectively relate, to make and use the same.

15 One of the objects of my invention is, to provide an automatically-actuated fuel injection valve of a novel type, in which mechanical actuation of the valve-closure element is dispensed with, and in place 20 thereof an automatic actuation by the fuel itself is substituted.

Another object is, to provide a fuel-injection valve which will to a greater extent than heretofore, be self-cleansing.

25 Still another object of this invention is, to provide a fuel-injection valve which, by slight modification will produce injection of fuel into the combustion chamber of the engine either in the form of a spray, or in 30 the form of a stream, which latter form is known as "solid injection."

My improved fuel-oil injection valve is illustrated in the accompanying drawings, which are hereinafter referred to, and form 35 a part of this specification.

In said drawings:

Figs. 1 and 2 illustrate the form of valve which is adapted to produce spray injection.

Figure 1 is a longitudinal section of both 40 the casing and the closure element.

Fig. 2 is a longitudinal section of the valve casing, the closure element being shown in elevation.

Fig. 3 is a transverse section on line 45 III-III of Fig. 2.

Figs. 4 and 5 illustrate the form of my valve which is adapted to produce solid injection:

Figure 4 is a longitudinal section of both 50 the casing and the closure element of said solid injection valve.

Fig. 5 is a longitudinal section through the casing of the valve, the closure element being shown in elevation.

Fig. 6 is a transverse section on line 55 VI-VI of Fig. 5.

Fig. 7 is a detail view of the solid injection nozzle.

The construction shown in Figs. 1, 2 and 3 is substantially as follows:

A valve casing 1 is provided which is substantially tubular in form, the bore of which is enlarged in diameter adjacent the outer end thereof to form a bearing and turbine chamber 2. At its inner end said bore is 60 reduced at 3 for the purpose of closely conforming to the diameter of the closure element adjacent its inner end, and for a further purpose which will presently be set 65 forth.

The closure element for said valve comprises a tubular member 4, having at its outer end an annular collar or flange 5 which serves a double function, namely, that of a bearing for said closure member, whereupon, at certain periodical intervals of its 70 operation it becomes revoluble, and the function of a turbine or motor adapted to be driven by the fuel oil as it enters said casing.

Ball bearings are provided for said collar 5, and the balls 6 upon the inner side of said flange or collar 5 rest upon the shoulder 7 of the valve-casing 1. The balls 8 upon the outer opposite side of said collar lie 75 between the outer face thereof and the adjacent face 9 of the cap 10. The adjustment of said cap 10 is such that it presses firmly upon its seat 11 and is caused so to do by 80 means of the annular nut 12, at the same time a considerable degree of pressure is also exerted upon the balls 8, and this pressure being transmitted to said collar 5, a 85 degree of longitudinal contraction or compression of said closure element is thereby caused, which, in turn, causes the inner, seating end face or point 13, to firmly seat upon the seating face 14 of the ejection orifice 15 at the inner end of said casing 1,

whereby said orifice is normally closed in 90 such a manner that a considerable degree of pressure of the fuel oil within the casing is required to longitudinally further compress said closure element to unseat its inner seating face and permit the ejection of fuel oil 95 from said orifice.

The method of securing said longitudinal resiliency of said closure element 4 may be 100

clearly understood by a reference to Fig. 1 of the drawings. It will be noted that said member 4 is circumferentially and transversely corrugated, and that said corrugated conformation appertains both to its periphery and to its interior wall. When, therefore, pressure is exerted upon the exterior surface of said member 4 by the fuel oil within said casing, said member will be caused to contract longitudinally, and the inherent resiliency will cause said member to expand again when said pressure is relieved.

In the assembly of the valve, a very slight amount of clearance is provided for between the inner or lower face of the collar 5 and the bearing balls 6 which are below the same, but the extent of said clearance is only such as would usually be provided by the allowance or tolerance for a running fit of this type of a bearing. This slight amount of clearance is shown in the drawing, but the extent of same is there considerably exaggerated for the sake of clear illustration.

The periphery of said collar 5 is formed into teeth or turbine vanes 16 and the fuel inlet 17 is tangentially disposed in said casing 1, and is positioned in operative relation to said collar and said vanes, so that when the fuel oil enters said duct 17 it impinges upon said vanes and will under certain phases of operation,—presently to be set forth—cause said closure member to revolve.

The conditions under which said closure member 4 is free to revolve and will be caused to do so are as follows:

The fuel oil is supplied through said tangential duct 17, by means of a plunger-pump, as usual, or it may be supplied by any means which will deliver the oil to the valve in periodical impulses, in accordance with the periods or cycle of the engine to which the valve is applied. At an interval of highest pressure of oil produced by said pump, said pressure often attains several hundred pounds per square inch. When said pump-delivery impulses occur, the first tendency of the resulting pressure is to press the closure element more firmly to its seat, then to slightly compress said element, whereupon said clearance between the lower face of said collar 5 and the bearing balls 6 is taken up, and thereafter, as the pressure continues to rise it causes said closure member to contract longitudinally and to such an extent that its point 13 is unseated from the seat 14, thus opening the ejection opening 15 and oil is ejected therefrom. At this ejection stage and state of longitudinal contraction of said closure member, said member is suspended from its bearing, pressure throughout its superficial area is balanced and said element is free to, and does revolve

by reason of the tangential entrance of the oil at duct 17 and its forceful impingement upon said blades 16.

The inner end of said closure element is formed into a guide 18, for which said reduced bearing section 3 in the casing 1 is provided. To provide for the ready passage of the oil past said guide 18, its periphery is spirally corrugated, the spiral disposition of said corrugations being for the purpose of more readily causing any solid or semi solid matter which may be in the oil or may tend to form at this point because of the heat, to be expelled from the valve.

In the cap 10, an air vent 19 is provided, which is closed by a cone-point set screw 20. Said vent is for the purpose of permitting the escape of air from the interior of the casing when fuel is first supplied thereto, whereupon the vent is closed.

Should the valve be inserted in the engine in an inverted position, said vent would then be unnecessary.

In the construction shown in Figs. 4 and 5, the ejection end of the closure element 4, is elongated to form a nozzle 23, through which the fuel is injected into the combustion chamber of the engine in a stream, instead of in the nature of a spray, as in the previously-described construction.

In this modified construction, both the casing 1 and the closure element are only slightly modified, all of said modification being at the inner end of the organization.

Referring especially to Fig. 7, the seating face 22, corresponds to the seating face 13 of Figs. 1 and 2. Below said seating face said closure element is elongated to form a nozzle 23, in the upper portion of the periphery of which a longitudinal groove 24 is formed; from the lower end of said groove a very small hole is drilled diagonally through the nozzle, from which it opens or emerges at its side and forms the outlet orifice 25 in the flattened area 26 at one corner of said nozzle. The inner end of the casing 1 is elongated somewhat at 27, to form a protective sheath for the nozzle.

The inner end of the bore of the closure element is hermetically sealed, in any suitable manner, as by a plug 21, to prevent the entrance of fluid therein.

Valves to produce the two forms of injection are provided for the reason that some manufacturers of oil engines advocate and employ spray injection, while others advocate and employ solid injection. It is my purpose to supply both requirements, hence neither one nor the other of these two forms are considered the preferred form.

It may now be helpful to a clear understanding of my construction to summarize the novel characteristics of the two main elements of my improved valve as follows:

The casing 1 is a tubular element arranged for the revoluble mounting of the closure element therein.

It has a tangentially-arranged oil inlet 5 adjacent its outer end.

It has an ejection opening at its inner end. The closure element 4 is tubular.

It is transversely, circumferentially corrugated, both externally and internally, 10 whereby it is caused to be longitudinally resilient.

It is adapted to be longitudinally contracted by the external pressure of fuel oil in the casing at approximately ejection pressure, and inasmuch as oil is supplied to the casing in impulses,—as by a plunger pump—said contraction is caused periodically.

It is revolubly mounted in its casing and is free to revolve at the contracted or compressed period.

During said revolubility, pressure throughout its entire superficial area is balanced.

During said revoluble period said element 25 is suspended from its bearing.

Its interior is hermetically sealed.

The revoluble function of the closure element causes the seating faces of the valve to be self-grinding and self-seating.

30 I claim the following:

1. A fuel-injection valve for oil engines comprising a tubular casing having a fuel-supply duct adjacent its outer end and a fuel-ejection orifice at its inner end, in combination with a longitudinally-contractile, tubular, revoluble closure element within said casing, having its inner end arranged to close said orifice, and means producing longitudinal contraction of said element for the ejection of fuel therefrom, and means imparting revoluble movement to said element during the ejection interval.

2. A fuel injection valve for oil engines comprising a tubular casing having a fuel-supply duct adjacent its outer end and a fuel-injection orifice at its inner end, in combination with a tubular, transversely-corrugated, longitudinally-contractile, revoluble closure element within said casing having its inner end arranged to normally close said orifice, means causing longitudinal contraction of said element to open said orifice for the ejection of fuel therefrom, and means imparting revoluble motion to said element when said ejection occurs.

3. A fuel-injection valve for oil engines comprising a tubular casing having a fuel-supply duct adjacent its outer end and a fuel-ejection opening at its inner end, in combination with a tubular, hermetically-sealed, transversely-corrugated, longitudinally-contractile, revoluble closure element within said casing having its inner end arranged to normally close said opening, means causing longitudinal contraction of

said element so as to open said orifice for the ejection of oil therefrom, and means imparting revoluble motion to said element when said ejection occurs.

4. A fuel-injection valve for oil engines 70 comprising a tubular casing having a fuel-inlet duct adjacent its outer end and a fuel-ejection opening at its inner end, in combination with a tubular, transversely-corrugated, longitudinally-contractile, periodically-balanced and revoluble closure element within said casing having its inner end arranged to normally close said opening, means causing periodical longitudinal contraction of said element to open said orifice 80 for the ejection of oil therefrom, and at the same period imparting revoluble motion to said element.

5. A fuel injection valve for oil engines comprising a tubular casing having a tangentially-disposed fuel-inlet duct adjacent its outer end and a fuel ejection opening adjacent its inner end, in combination with a tubular, longitudinally-contractile, revoluble closure element within said casing, 90 adapted to normally close said ejection opening when the pressure of fuel within said casing is less than ejection pressure, and to be longitudinally contracted to open said ejection opening when the pressure of 95 said fuel reaches approximately ejection pressure, and a turbine collar carried by said element positioned relative to said tangential inlet duct so as to be revolubly actuated by the fuel entering thereat when said element is longitudinally contracted.

6. A fuel ejection valve for oil engines comprising a tubular casing having a tangentially-disposed fuel-inlet duct adjacent its outer end and a fuel ejection opening 105 adjacent its inner end, in combination with a tubular, longitudinally-contractile, revoluble closure element within said casing adapted to normally close said ejection opening when the pressure of the fuel oil within said casing is less than ejection pressure and to be longitudinally contracted by external pressure of said fuel when said pressure reaches approximately ejection pressure, and a turbine collar carried by said element positioned relative to said tangential inlet duct, so as to be revolubly actuated 110 by the fuel entering thereat at the instant of ejection.

7. A fuel injection valve for oil engines 120 comprising a tubular casing having a tangentially-disposed fuel-inlet duct leading into the same adjacent its outer end and a fuel ejection opening at its inner end, in combination with a tubular, longitudinally-contractile, circumferentially-corrugated, periodically-revoluble closure element within said casing adapted to normally close said ejection opening when the pressure of fuel 125 within said casing is less than ejection pressure.

sure and to be longitudinally contracted to open said opening when the pressure of said fuel reaches approximately injection pressure, in which contracted state the fuel pressure upon the whole superficial area of said element is balanced and the same becomes revoluble, and a turbine collar carried by said element positioned relative to said tangential duct so that the fuel entering thereat revolubly actuates said closure element at said revoluble period.

8. A fuel injection valve for oil engines comprising in combination a tubular casing having a tangentially-arranged fuel-inlet duct leading into the bore thereof adjacent to the outer end of same and a fuel-ejection opening at its inner end, the bore of said casing adjacent its outer end being enlarged to form a bearing and turbine chamber, the junctional point of said enlarged portion of said bore with the smaller portion thereof forming a square shoulder arranged to serve as a bearing face; a tubular, longitudinally-resilient and contractile, revoluble closure element within said casing arranged at its inner end to normally close said opening, said element, by reason of said resiliency

being longitudinally contractile by the pressure upon its exterior surface when said pressure reaches ejection pressure and whereby said inner end of said element is caused to recede from and to open said ejection opening, a collar carried by said closure element adjacent its outer end, bearing balls resting upon said shoulder of said casing, said collar arranged with its inner face in close proximity to said balls, bearing balls resting upon the upper face of said collar, a cap carried by said casing having a bearing-face adapted to contact with said last-mentioned balls, means causing said cap to exert pressure upon said balls and therethrough to said closure element to cause its lower point to securely close said ejection opening, except during said contracted period, the periphery of said collar being provided with turbine blades which are positioned in actuating relation to said tangential duct so as to be revolved during said contracted period by the fuel entering thereat.

In testimony whereof I affix my signature.

FRANZ CARL TEUFL.
